UNITED STATES PATENT OFFICE.

WILLIAM G. COX, OF CLEVELAND, OHIO, ASSIGNOR TO COX BRASS MANUFACTURING COMPANY, OF ALBANY, NEW YORK, A CORPORATION OF NEW YORK.

DESIGN FOR AN AUTOMOBILE-BUMPER.

58,718.

Specification for Design.

Patented Aug. 30, 1921.

Application filed May 10, 1921. Serial No. 468,426. Term of patent 7 years.

To all whom it may concern:

Be it known that I, WILLIAM G. Cox, a citizen of the United States, residing at Cleveland, in the county of Cuyahoga and State of Ohio, have invented a new, original, and ornamental Design for an Automobile-Bumper, of which the following is a specification, reference being had to the accompanying drawing, forming part thereof, in which—

Figure 1 is a plan view, and Fig. 2 a front view of an automobile bumper, showing my new design.

I claim:

The ornamental design for an automobile bumper, as shown.

WILLIAM G. COX.
